UNITED STATES PATENT OFFICE.

JOHN BOULTBEE BROOKS, OF BIRMINGHAM, AND JOHN HOLT, OF ASTON,
ENGLAND.

CYCLE-SADDLE.

No. 823,916.

Specification of Letters Patent.

Patented June 19, 1906.

Application filed November 6, 1905. Serial No. 286,163.

To all whom it may concern:

Be it known that we, JOHN BOULTBEE BROOKS, residing at Criterion Works, Great Charles street, Birmingham, and JOHN HOLT, residing at 97 Frederick road, Aston, near Birmingham, England, subjects of the King of Great Britain, have invented certain new and useful Improvements in Cycle-Saddles, of which the following is a specification.

This invention has relation to cycle-saddles, and has for its object to provide the seats of such saddles with an improved system of supports which admits of the leather being left in a moderately-tensioned condition so that its natural softness and flexibility is conserved and comfort is insured, while at the same time the proper shape of the seat is preserved, lateral stretching or spreading is prevented, and an effective support for the load is provided.

Figure 1 of the accompanying drawings represents an under side plan of a cycle-saddle constructed in accordance with our invention. Fig. 2 is a cross-section of the said saddle, taken upon the dotted line x , Fig. 1, and looking toward the cantle end. Fig. 3 is a longitudinal section upon the dotted line x^2 , Fig. 1, while Fig. 4 is a section of the after part, taken diagonally upon the dotted line x^3 , Fig. 1. Fig. 5 is an under side plan, partly in horizontal section, of a saddle provided with a system of tension seat-supports, showing a modification. Fig. 6 is an end view, partly in vertical section, of a portion of the construction as illustrated by Fig. 5.

The same reference-numerals indicate corresponding parts in the said figures.

In the particular arrangement represented in the said figures the seat 10 is carried between a cantle or back plate 11 and a peak-plate 12, supported by an underframing 13 in the usual way; but the leather is left in a moderately-tensioned state, so that its natural softness and pliability are preserved. The cantle-plate has attached to its middle part a bracket-like stretcher member 14 of the seat-sustaining system, which consists of an arm or tongue fashioned from spring-wire and is arranged to extend forwardly in an approximately horizontal plane underneath the saddle to such a distance that its free end will come at about the center of the body part of the seat, while upon each side of the said stretcher member is disposed a strap, band,

or like supporting medium 15, preferably of leather, and directed from the cantle-plate obliquely inward toward the inner or yielding ends 16 of the stretcher, to which they are collectively connected or coupled by forming the said ends into loops or eyes to which the inner extremities of the straps are riveted or otherwise attached, while their outer ends are riveted in between the extremities of the cantle-plate and the leather. With such an arrangement when the saddle is loaded the flexible stretcher member (or combined stretcher and coupling member) and the oblique supporting media of the triangulated system are depressed and the said stretcher is transformed into an active spring which operates in unison with ties or connected series of supporting-straps for flexibly sustaining or upholding the body part of the seat, while still preserving the shape of the same and conserving the natural softness of the leather.

The flexible stretcher member may be made in the form of a steel tongue, and instead of anchoring its outer end immovably to the cantle-plate it may be adjustably attached thereto by screw connections, which admit of its movement in the longer direction of the saddle for the purpose of tensioning or stretching the diagonal supporting-straps or the like. (See Figs. 5 and 6.)

18 is the stretcher member, whose free inner end supports and links together the inner extremities of the pair of diagonally or obliquely-disposed seat-supporting straps 19, while the outer ends of the branches or sides of the said stretcher are made to take or socket into plain holes 20 in a pair of adjusting-screws 21, which are engaged with the wormed holes 22 of a pair of brackets 23, secured to the cantle-plate, the arrangement being such that when the screws are wormed inwardly through the brackets they force the stretcher member (around the plain extremities of which they freely swivel) inward with them, and thus tension or tighten up the connected seat-supporting devices to a proportional degree.

Having fully described our invention, what we desire to claim and secure by Letters Patent is—

1. In a cycle-saddle, the combination of a seat, diagonally-arranged flexible devices under the rear portion of the seat and support-

ing the latter, and yielding means connected to the inner end of the said devices and to the rear portion of the seat.

2. In a cycle-saddle, the combination of a seat, diagonally-directed flexible seat-supporting devices arranged under the rear portion of the said seat, and yielding bracket means connected to the inner ends of the said devices and to the seat-cantle, the outer ends 10 of the devices being also attached to the cantle.

3. In a cycle-saddle, the combination of a seat, means for upholding the seat-leather from the under side and consisting of diag-

onally - arranged flexible tension devices, 15 stretcher means attached to the inner ends of the said devices and also movably connected to the cantle of the saddle, the outer ends of the said upholding devices being also attached to the cantle of the saddle.

In testimony whereof we have hereunto set our hands in presence of two subscribing witnesses.

JOHN BOULTBEE BROOKS.
JOHN HOLT.
